Primary Examiner — Sandra Snapp*Assistant Examiner* — Caitlin Mackenzie Williams(74) Attorney, Agent, or Firm — Banner & Witcoff, Ltd.(57) CLAIM

The ornamental design for a shoe as shown and described.

DESCRIPTION

FIG. 1 is a front perspective view of a shoe showing my new design;
 FIG. 2 is a side view thereof;

FIG. 3 is an opposite side view thereof;

FIG. 4 is an opposite side front perspective view thereof;

FIG. 5 is a rear view thereof;

FIG. 6 is a rear perspective view thereof; and,

FIG. 7 is an opposite side rear perspective view thereof.

The darker toned even-length broken lines and zig zag broken lines depict stitching which exclusively forms the claimed design. The lighter toned uneven-length broken lines depicting the remainder of the shoe form no part of the claimed design.

1 Claim, 7 Drawing Sheets(56)
